COIN-CONTROLLED MECHANISM.

1,081,562.

Specification of Letters Patent. Patented Dec. 16, 1913.

Application filed February 1, 1911. Serial No. 605,852.

To all whom it may concern:

Be it known that I, JAMES E. ALLISON, a citizen of the United States, and a resident of the city of St. Louis and State of Missouri, have invented a new and useful Improvement in Coin-Controlled Mechanisms, of which the following is a specification, the principle of the invention being herein explained and the best mode in which I have 10 contemplated applying that principle, so as to distinguish it from other inventions.

The present invention relates in general to coin controlled mechanism and its particular object is the provision of a mechanism which will allow movement of a given member only upon the insertion of a coin of determined size in the mechanism and which will securely lock that member against movement under any other condition.

The annexed drawing and the following description set forth in detail certain mechanism embodying the invention, such disclosed means constituting, however, but one 25 of various mechanical forms in which the principle of the invention may be used.

In said annexed drawing: Figure 1 is a vertical section of my improved mechanism; Fig. 2 is a horizontal section on the line 30 C—C in Fig. 1, certain parts being removed, the line A—A in Fig. 2 indicating the section of Fig. 1; Fig. 3 is a section on the line B—B in Fig. 2; and Fig. 4 is a detailed section on the line D—D in Fig. 1.

35 My mechanism may be housed in any suitable manner, but I have illustrated it as installed in housing 1 which will preferably contain separate spaces for the reception of the mechanism and for the reception of coins 40 passed through the mechanism respectively. The mechanism proper comprises a rotatable shaft 3 journaled in a suitable frame and it is the movement of shaft 3 which is primarily to be controlled, the shaft 3 carrying 45 any desired member whose movement is to be ultimately controlled. A disk 4 is secured on shaft 3 and is provided with a plurality of substantially radial teeth 5 which may be called forwardly facing teeth. The disk 50 4 is also provided with a peripheral groove 6 adjacent to each tooth 5, which may be conveniently formed by securing a plate 7 between two side plates, the side plates and

the plate 7 collectively forming the disk. A pivotally mounted pawl 8 is so positioned 55 as to engage one of the teeth 5 on the disk 4 upon forward rotation of the shaft and a spring 9 normally retains the pawl 8 in such position that it is operative to engage a tooth 5. A chute 10 opening exteriorly of 60 the housing 1 extends substantially to the periphery of disk 4 and a dog 11 prevents a coin 26 which may be inserted through the chute from falling backwardly out of the groove 6. A convenient device for centering the chute 10 with relation to the groove 6, is to provide a cross bar 12 secured to the respective sides of the housing 1 and to have ears 13 carried by bar 12 straddle the chute 10. In each of the ears 13 is a 70 screw 14 and obviously by extending or retracting the screws 14 the chute 10 may be accurately centered. A chute 15 is positioned to receive a coin 26 after it has passed through the mechanism and to convey the 75 coin to the partitioned space in the lower part of the housing 1. A disk 16 is also secured on shaft 3 and is provided with a plurality of rearwardly facing teeth 17. A pivoted pawl 18 is positioned to engage successive teeth 17 and a spring 19 normally retains the pawl 18 in engagement with the teeth 17. Still another disk 20 is secured 80 on shaft 3 and is formed with substantially radial forwardly facing teeth 21. A pivoted 85 lever 22 is normally in contact with one of the teeth 21 and a spring 23 pulls the lever 22 against the tooth 21.

The operation of the mechanism is as follows: In describing the operation it may be 90 assumed that the mechanism is to be used to allow a turn-stile to make successive partial revolutions upon the insertion of successive coins in the mechanism. To adapt the mechanism for this use a star wheel 24 95 will be secured to shaft 3 outside of the housing 1 and the arms of the turn-stile will successively engage teeth 25 of the star wheel. Normally the turn-stile can be rotated but slightly because it is in engagement with star wheel 24 which is locked against any except slight rotation by pawl 8 which will engage with one of the teeth 5 on disk 4. Neither can the star wheel be rotated in a reverse direction because the 100 pawl 18 is in engagement with one of the

teeth 17 on disk 16. Moreover the shaft will be maintained normally in the position in which it is shown in Fig. 1 by means of the lever 22 which is pressing against one of the teeth 21 on disk 20. Assume now that a coin is inserted through chute 10. The coin will be conducted by the chute into the groove 6 in the position shown by the full line coin in Fig. 1. On rotation of the shaft the coin is pushed backward until it reaches the end of the groove but on further rotation the coin will raise the pawl 8 so that the tooth 5 may pass beneath it and therefore the turn-stile may be rotated. After the tooth 5 has passed the end of pawl 8, the pawl 18 will engage the succeeding tooth 17 so that the shaft and therefore the turn-stile cannot be reversely rotated. When the turn-stile and hence the shaft have been rotated the previously determined portion of a revolution, the pawl 8 engages the succeeding tooth 5 and prohibits further forward rotation of the shaft and turn-stile. The mechanism is now in its normal position again.

Other modes of applying the principle of my invention may be employed instead of the one explained, change being made as regards the mechanism herein disclosed, provided the means stated by the following claim or the equivalent of such stated means be employed.

I therefore particularly point out and distinctly claim as my invention:

In mechanism of the class described, the combination of a rotatable shaft; a disk secured to said shaft and provided with forwardly facing substantially radial teeth; a pawl normally in position to engage one of said teeth, said disk having a peripheral groove adjacent each tooth designed to receive a coin adapted, on rotation of said shaft, to move said pawl from such position; a spring tending to retain said pawl in such position; a second disk secured to said shaft and provided with rearwardly facing substantially radial teeth; a second pawl normally in engagement with one of the teeth of said second disk; a spring tending to retain said second pawl in such engagement; a third disk secured to said shaft and provided with forwardly facing substantially radial teeth; a lever contacting with the face of one of the teeth of said third disk; and a spring tending to continuously press said lever against the successive teeth upon rotation of said shaft.

Signed by me this 23rd day of January, 1911.

JAMES E. ALLISON.
